ASH TRAY OR THE LIKE

Odvar Andresen, Brooklyn, N. Y.

Application November 16, 1950, Serial No. 13,017

Term of patent 7 years

(Cl. D85—2)

To all whom it may concern:

Be it known that I, Odvar Andresen, a subject of the King of Norway, residing in Brooklyn, county of Kings, and State of New York, have invented a new, original, and ornamental Design for an Ash Tray or the like, of which the following is a specification, reference being had to the accompanying drawing, forming part thereof, and in which:

I claim:

The ornamental design for an ash tray or the like, as shown.

ODVAR ANDRESEN.
